UNITED STATES PATENT OFFICE.

WILLIAM P. SACKETT, OF PHILADELPHIA, PENNSYLVANIA, ASSIGNOR TO
BAILEY, BANKS, & BIDDLE, OF SAME PLACE.

DESIGN FOR A BADGE.

SPECIFICATION forming part of Design No. 21,394, dated March 8, 1892.

Application filed February 8, 1892. Serial No. 420,789. Term of patent 7 years.

To all whom it may concern:

Be it known that I, WILLIAM P. SACKETT, a citizen of the United States, residing in the city and county of Philadelphia, State of Pennsylvania, have invented and produced a new and original Design for a Badge, of which the following is a specification, reference being had to the accompanying drawings, forming part thereof.

10 The leading feature of my design for a badge is a pennant having a field of different shades thereon, the divisional lines between the shades being oblique.

In the drawing, A designates a badge con-

sisting of the forked pennant B and the staff 15 C. The field of the pennant is of different shades, as at D and E, the divisional line between the same being oblique. The shades of the field represent black and orange, the colors of Princeton College. 20

I claim—

The design for a badge, substantially as shown and described.

WILLIAM P. SACKETT.
